UNITED STATES PATENT OFFICE.

HORACE A. CARTER, OF NEEDHAM HEIGHTS, MASSACHUSETTS, ASSIGNOR, BY MESNE ASSIGNMENTS, TO THE WILLIAM CARTER CO., OF NEEDHAM HEIGHTS, MASSACHUSETTS, A CORPORATION OF MASSACHUSETTS.

KNITTED GARMENT.

1,145,402.

Specification of Letters Patent.

Patented July 6, 1915.

Application filed December 9, 1911. Serial No. 664,793.

To all whom it may concern:

Be it known that I, HORACE A. CARTER, a citizen of the United States, and a resident of Needham Heights, in the county of Norfolk and State of Massachusetts, have invented an Improvement in Knitted Garments, of which the following description, in connection with the accompanying drawings, is a specification, like characters on the drawings representing like parts.

This invention relates to knitted garments and particularly to knitted undershirts or undergarments.

In order that the principle of the invention may be readily understood, I have disclosed a single embodiment thereof in the accompanying drawing, wherein—

Figure 1 is a plan view of the upper portion of a knitted undershirt or union suit embodying my invention; Fig. 2 is a detail thereof upon an enlarged scale; Fig. 3 is a top plan view of a portion of the preferred embodiment of elastic stretch limiting band characteristic of my invention; Fig. 4 is an underneath view thereof; and Fig. 5 is a section taken through the neck of the garment on the line 5—5 of Fig. 2.

Knitted garments and particularly knitted undershirts and union suits are customarily composed of yarn so knitted that the wales thereof run substantially lengthwise of the garment throughout substantially the entire body thereof, as indicated at 1 in Figs. 1 and 2, while the neck opening thereof is usually composed of a knitted strip, the wales whereof extend circumferentially of the neck as indicated at 2 in Fig. 2. Such a neck opening is objectionable because it stretches unduly in use, so that this portion of the garment no longer fits the wearer properly. In accordance with my invention, I provide an expansible band extending circumferentially of the neck portion of the garment. This band is itself somewhat expandable, but only within well defined limits, which are materially less than those of the knitted neck portion of the shirt or other garment, thus preventing the neck from being stretched as heretofore to the elastic limits of the knitted material itself or to an extent approaching the same. This band is preferably elastically sewed by any suitable elastic sewing machine stitch to the neck portion of the garment. I secure the best re-

sults by employing a band of woven material cut upon the bias as indicated at 3 in Figs. 3 and 4, this band being preferably inwardly folded at each edge as indicated at 4—4 in Fig. 5, so that the band when sewed by an elastic sewing machine stitch as indicated at 5 in Fig. 2, is of double thickness. A strip or band of woven material cut upon the bias is more expansible longitudinally than a strip or band so cut that the warp or weft threads extend in parallelism to the edges and ends thereof. At the same time the expansibility of such a band is materially less than that of the knitted fabric itself, and therefore the amount of stretch of the neck portion of the garment is limited by the amount of stretch of said bias band.

While preferably the neck portion of the garment is composed of a knitted strip 2, the wales thereof extending circumferentially of the neck, it is to be understood that the body portion 1 may be extended to the extreme edge of the neck and have the said bias band applied thereto, whereby the lateral stretch of the garment is limited as described. Within the scope of my invention, other openings, as for example, the wrist and ankle openings, may be similarly provided with the described stretch limiting band. The said band preferably extends circumferentially about the neck as indicated in Fig. 1 and preferably at the extreme upper edge thereof, as this is the point most liable to be unduly stretched. It will be observed that the neck band or neck portion of the garment is itself quite highly elastic and that the stretch limiting band 3, while being materially expansible, can itself be stretched only within certain well defined limits, which are materially less than those of the knitted goods itself. Furthermore, the character of the stitches 5 whereby the band 3 is sewed to the neck portion of the garment is such that said stitches and band itself may stretch or give in use while still preventing undue stretch of the knitted portion of the garment. A knitted undergarment or similar article formed in accordance with my invention retains the proper shape of the neck or other opening and preserves the tight fitting character thereof. The bias strip may be expanded or distended by a pulling action, and thus if the neck opening

of the garment be found too small, it can thus be enlarged. After having been thus expanded, it will not substantially contract or shrink. Frequently the neck measure is 5 disproportionately large as regards the bust measure, and thus a garment having a normal neck opening for a given size will fit the wearer too tightly. In such case, the neck opening can be readily distended as 10 described, and yet having been distended to a predetermined limit, it cannot further expand, nor will it substantially contract even after washing or laundrying.

Having thus described one illustrative 15 embodiment of my invention, I desire it to be understood that although specific terms are employed, they are used in a generic and descriptive sense and not for purposes of limitation, the scope of the invention 20 being set forth in the following claims.

Claims.

1. A knitted garment having a highly 25 expansible, opening-bordering portion and means to permit manual stretching of said portion to a fixed limit and to effect the retention of said portion in said stretched condition, said means comprising a bias, woven strip secured to the edge wales of said opening and extending circumferentially thereof, said bias strip being materially expansible, 30 but to a well defined, predetermined limit materially less than the elastic limit of said opening-bordering portion and substantially non-contractible after expansion or washing, whereby said strip and the opening 35 bordering portion to which it is attached may be manually and permanently distended to obtain an opening fitting the wearer.

In testimony whereof, I have signed my 40 name to this specification, in the presence of two subscribing witnesses.

HORACE A. CARTER.
